(57) **CLAIM**

The ornamental design for a portion of a wear member for earth moving equipment, as shown and described.

DESCRIPTION

FIG. 1 is a perspective view showing our new design:

FIG. 2 is a top plan view thereof;

FIG. 3 is a bottom plan view thereof;

FIG. 4 is a side elevation view of one side thereof;

FIG. 5 is a side elevation view of the opposite side thereof;

FIG. 6 is a front elevation view thereof;

FIG. 7 is a rear elevation view thereof; and,

FIG. 8 is a perspective view of the portion of a wear member of FIG. 1 shown in use with an exemplary bucket.

The broken lines illustrate features that form no part of the claimed design. The dot-dash lines illustrate boundaries that form no part of the claimed design.

1 Claim, 7 Drawing Sheets
